UNITED STATES PATENT OFFICE

119,802

DESIGN FOR AN ASH RECEPTACLE OR SIMILAR ARTICLE

Winston Fuller, Portland, and Kenneth A. Walsh,
Brockton, N. Y.

Application April 25, 1939, Serial No. 84,552

Term of patent 7 years

To all whom it may concern:

Be it known that we, Winston Fuller and Kenneth A. Walsh, citizens of the United States, residing at Portland and Brockton, respectively, in the county of Chautauqua and State of New York, having invented a new, original, and ornamental Design for an Ash Receptacle or Similar Article, of which the following is a specification, reference being had to the accompanying drawing, forming part thereof; and in which

Figure 1 is a plan view of an ash receptacle or similar article showing our new design;
Figure 2 is a side elevational view; and
Figure 3 is an end elevational view thereof.

We claim:

The ornamental design for an ash receptacle or similar article, substantially as shown.

WINSTON FULLER.
KENNETH A. WALSH.
